US00D957534S

(12) **United States Design Patent** (10) **Patent No.:** **US D957,534 S**
(45) **Date of Patent:** **** Jul. 12, 2022**

(54) **DRIFTING KART**

(71) Applicant: **RAZOR USA LLC**, Cerritos, CA (US)

(72) Inventors: **Ali Kermani**, Huntington Beach, CA (US); **Robert Hadley**, Cerritos, CA (US); **Robert (Wei-Pin) Chen**, San Marino, CA (US)

(73) Assignee: **Razor USA LLC**, Cerritos, CA (US)

(**) Term: **15 Years**

(21) Appl. No.: **29/741,692**

(22) Filed: **Jul. 15, 2020**

Related U.S. Application Data

(63) Continuation of application No. 29/696,443, filed on Jun. 27, 2019, now Pat. No. Des. 890,854, which is a continuation of application No. 29/665,460, filed on Oct. 3, 2018, now Pat. No. Des. 852,893, which is a continuation of application No. 29/612,025, filed on Jul. 27, 2017, now Pat. No. Des. 830,469, which is a continuation of application No. 29/565,023, filed on May 17, 2016, now Pat. No. Des. 793,481.

(57) **CLAIM**

The ornamental design for a drifting kart, as shown and described.

DESCRIPTION

FIG. 1 is a top, front, left-side perspective view of a drifting kart of our design;

FIG. 2 is a bottom, front, right-side perspective view thereof;

FIG. 3 is a front elevation view thereof;

FIG. 4 is a rear elevation view thereof;

FIG. 5 is a right-side elevation view thereof;

FIG. 6 is a left-side elevation view thereof;

FIG. 7 is a top plan view thereof; and,

FIG. 8 is a bottom plan view thereof.

The broken lines illustrate portions of the article that form no part of the claimed subject matter.

1 Claim, 7 Drawing Sheets
